UNITED STATES PATENT OFFICE.

CAREY PHILLIP GABLE, OF RUSTON, LOUISIANA.

DITCHING-MACHINE.

No. 802,280.

Specification of Letters Patent.

Patented Oct. 17, 1905.

Application filed June 19, 1905. Serial No. 266,086.

To all whom it may concern:

Be it known that I, CAREY PHILLIP GABLE, a citizen of the United States, residing at Ruston, in the parish of Lincoln and State of Louisiana, have invented a new and useful Improvement in Ditching-Machines, of which the following is a specification.

My invention is in the nature of a ditching-machine designed to dig new ditches or clean out old ones; and it consists in the novel construction and arrangement of parts of a portable machine designed to take up the dirt and deposit it on one side or the other of the ditch, as hereinafter more fully described with reference to the drawings, in which—

Figure 1 is a side elevation, and Fig. 2 a top plan view, of the machine.

In the drawings, A A represent two parallel and longitudinally-arranged base-bars, formed at one end like runners to permit the machine to be drawn across the field after the manner of a sled. These base-bars are connected by cross-bars B B', and on each base-bar are mounted standards C C, above which 25 and to which is securely fastened the two parallel sills D D of a deck E.

On the cross-bar B in a suitable step-bearing is mounted a vertical derrick-post F. To this post is firmly attached an inclined derrick-arm G, which extends upwardly and outwardly and whose upper end is connected to the top of the derrick-post by a tension-brace H.

I is a rotary adjustable platform fixed rigidly to the derrick-post and adapted to turn with it about its vertical axis. This platform rests on top of the deck E and, if desired, may be provided with friction-rollers where it moves upon the deck. This platform and the 35 parts carried by it, however, are about balanced by the derrick-arm and its parts, so that it moves easily about its pivotal center. This platform has erected upon it four standards J, carrying at their upper ends side bars in 40 which are journaled the ends of two horizontal cross-shafts K L. One of these shafts K is provided with a crank-handle k or power-pulley, by which it is turned, and has also rigidly keyed to it a gear-wheel k', which meshes 45 with a smaller gear-wheel l, fixed to windlass-shaft L, and on this shaft beside the gear-wheel l is a winding-drum l'. On this winding-drum is wound the end of a cable M, which passes over a sheave f in the derrick-post and thence over one of two sheaves g g' in the outer end of the derrick-arm, and thence

down to a sheave in a tackle-block N, and thence up to the other sheave g' in the derrick-arm and down again to the hitch-eye of the tackle-block. To the lower side of the 60 tackle-block is hitched the bail of a scoop-bucket O, having a hinged bottom o, which is to be equipped in the usual way with a trip-latch.

The rotary platform attached to the derrick-post is of less length than the deck below it, and in the deck in rear of the platform is mounted to turn about a vertical axis a capstan or turning-post P, having at its upper end a cross-head p, forming handles for turning 65 it. The lower end of this turning-post is stepped in a bearing in the cross-bar B' of the lower frame, and to the lower portion of this post is rigidly attached a horizontal sprocket-wheel Q, around which passes an endless chain 70 belt R, which extends to and surrounds a similar sprocket-wheel Q, fixed rigidly to the lower portion of the derrick-post, so that when the turning-post is rotated by a man standing on the deck in rear of the rotary 75 platform the latter, together with the derrick-post, its arm, and the load in the bucket, may be swung from side to side to deposit the dirt to one side of the ditch, as seen in dotted lines.

In the operation of this machine the scoop 80 or bucket is permanently connected to the tackle-block by its bail and is filled by sitting on the point (as any other ordinary scraper) and turning the crank. When the scoop comes into line with the sheaves, it is drawn 85 up. To aid in filling, the scoop has on its rear end one or more handles h, as seen in Fig. 1. After the scoop is raised the derrick-post, the platform, the derrick-arm, and the loaded bucket are then together swung to one 90 side by the manipulation of the capstan or turning-post and the earth dumped in the usual way by tripping the latch of the bucket.

In making use of my invention I may operate it either by hand, horse-power, steam, or 95 by any other kind of motor.

Having thus described my invention, what I claim as new, and desire to secure by Letters Patent, is—

1. An excavating-machine, comprising a 100 base-frame having an upper deck, a platform mounted above said deck but leaving the rear part of the same exposed, a derrick-post with outwardly-extending arm, winding-gears mounted upon the platform and having a cable 105 extending to the outer end of the derrick-arm, a sprocket-wheel fixed to the derrick-post be-

low the deck, a vertical turning-post arranged in bearings in rear of the platform and extending above the exposed rear end of the deck, a sprocket-wheel fixed to the lower portion of the turning-post, and a chain belt connecting the two sprocket-wheels substantially as and for the purpose described.

2. An excavating-machine, comprising a deck having a vertically-pivoted derrick with 10 excavating devices at one end and a vertically-pivoted turning-post at the other end, mechanism connecting the two for turning the derrick and a windlass and frame mounted above the deck and fixed to the derrick and resting 15 upon the deck at a point in front of the turning-post substantially as described.

3. An excavating-machine comprising two base-bars formed as runners, vertical standards mounted on the same and a deck carried 20 by said vertical standards; a platform mount-

ed above the deck, but leaving the rear part of the same exposed, standards and journal-bars mounted on the platform, a driving-shaft with gear-wheel and a windlass with gear-wheel both mounted upon the platform-frame, 25 a vertical derrick-post having a braced and outwardly-extending arm, a cable extending from the windlass to the outer end of the derrick-arm, a tackle-block attached to the cable, a vertical turning-post arranged upon the 30 deck in rear of the platform and having an attached sprocket-wheel below the deck, a chain belt passing around the sprocket-wheel, and a second sprocket-wheel fixed to the derrick-post and embraced by the chain belt substantially as and for the purpose described. 35
